SHOE CONSTRUCTION

Bertino Dutra da Silva, New York, N. Y.

Application April 2, 1941, Serial No. 386,532

1 Claim.

(Cl. 36—36)

This invention relates to new and useful improvements in shoe constructions and more particularly to a detachable heel for shoes.

The principal object of the present invention is to provide a shoe construction in which the heel may be easily detached from the shoe and replaced by a new one with but a minimum of effort on the part of the repairer.

Another important object of the invention is to provide a shoe construction which includes a readily detachable heel which can be replaced when it becomes worn without the necessity of employing a skilled shoe repairer.

Other objects and advantages of the invention will become apparent to the reader of the following specification.

In the drawings:

Figure 1 represents a perspective bottom view of a shoe showing the improved heel construction in partly applied position.

Figure 2 is an enlarged fragmentary side elevational view with the heel portion in section.

Figure 3 is a top plan view of the heel and its plate.

Figure 4 is a cross sectional view on the line 4—4 of Figure 3.

Figure 5 is a longitudinal sectional view taken substantially on the line 5—5 of Figure 6.

Figure 6 is a bottom plan view showing the seat heel plate and heel plate in connected relation.

Figure 7 is a sectional view taken substantially on the line 7—7 of Figure 6.

Figure 8 is a section taken substantially on the line 8—8 of Figure 6.

Figure 9 is a plan view of the heel attached plate.

Figure 10 is a cross section on the line 10—10 of Figure 9.

Figure 11 is a section taken substantially on the line 11—11 of Figure 9.

Figure 12 is a plan view of the seat heel attached plate.

Figure 13 is a section on the line 13—13 of Figure 12.

Figure 14 is a section on the line 14—14 of Figure 12.

Referring to the drawings wherein like numerals designate like parts, it can be seen that the structure represented in the drawings consists of four main parts, namely, the shoe proper 5, a detachable heel 6, a plate 7 carried by the heel 6 and a plate 8 carried by the seat heel 9 of the shoe 5.

The heel may be leather, rubber or any other material and has its forward edge portion stepped off as at 10 to accommodate the shoe sole 11. The plate 7 coincides with the configuration of the heel 6 and is secured upon the heel 6 by nails or the like 12. It being preferable that the top of the heel have a basin therein upon the bottom of which the plate 7 is disposed and

secured so that this plate will not be visible from the side of the shoe. This is also true of the plate 8 which is secured to the seat heel 9 of the shoe 5, this plate 8 also being concealed by the side wall of the basin formed top of the heel 6.

The heel plate 7 has a pair of parallel slots 13, 13 therein and a relatively large rectangular-shaped opening 14 at its intermediate portion. As shown in Figure 4, the heel 6 just below the slot 13 in the plate 7 is formed with channels 15, while just below the rectangular-shaped opening 14 in the plate 7, a pocket 16 is formed in the heel 6.

The seat heel plate 8 coincides with the configuration of the plate 7 and has a pair of parallel disposed struck-out L-shaped members 17 which ride in the slots 13 and grooves 15 and also a struck-out tongue 18 having an upwardly curved lip 19. This plate 8 also has a downwardly struck-out cleat 20. The plate 8 is secured to the seat heel by sewing or tacking.

As is suggested in Figure 1, by registering the slot 13 with the member 17 of the plate 8, the heel 6 can be slid into position with the cleat 20 and the spring tongue 18 in substantial abutting relation with the ends of the pocket 14.

The heel 6 is formed with a vertically disposed opening 22 through which an elongated nail or other implement can be disposed in order to flex the tongue 18 and dislodge the same from the pocket 16 and opening 14, to the end that the heel 6 can be slid off of the plate 8 conveniently.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

In a shoe construction, a seat heel, a heel, a plate secured to the heel, said plate being formed with a pair of spaced guide slots extending inwardly from the inner edge thereof, said plate having a substantially rectangular opening, said heel being formed with recesses over which portions of the plate at the slots and opening overhang, a second plate attached to the seat heel, said second plate being provided with a pair of L-shaped members extending inwardly from the inner edge thereof and adapted to be received by certain of the recesses and the slots, said second plate being struck out to provide a spring tongue for disposition through the opening of the first plate and into the corresponding recess and a cleat depending from the second plate and adapted to engage under the first plate at the rear edge of the opening therein when the plates are in connected relation.
